UNITED STATES PATENT OFFICE

ALFRED N. GOLDSMITH AND JULIUS WEINBERGER, OF NEW YORK, N. Y., ASSIGNORS
TO RADIO CORPORATION OF AMERICA, A CORPORATION OF DELAWARE

TELEVISION SYSTEM

Application filed March 25, 1929. Serial No. 349,652.

The present invention relates to television systems and more particularly to television systems wherein the television signal, the synchronizing signal and a speech signal accompanying the television signal are all transmitted simultaneously.

In the most practical and commercial developments of the various types of television systems it has been found necessary and desirable to transmit a synchronizing frequency which, for example, may consist of an audio frequency tone transmitted simultaneously with the television signal. This is necessary so that proper synchronization between the transmitter and receiver of a television system is maintained and the necessity of constantly framing the received picture by manual means is avoided. When the synchronizing signal is transmitted absolute constant framing of the received picture is obtained and all hunting in the apparatus is avoided.

It is also desirable at most times to send a speech or music accompaniment on the same channel with the television signal so that the sight of the received picture may be accompanied by speech or music occurring simultaneously with the various movements or actions in the received picture.

Therefore, one of the principal objects of the present invention is to provide a method and arrangement for accomplishing all of these above named desirable results simultaneously.

A further object of our invention is to provide a method and apparatus whereby the television and sound transmission channel may be so arranged that the combined width thereof will not exceed 100 kilocycles. This band width has been found to be most advantageous from the point of view of convenience and economy of wave channels.

Other and ancillary objects of our invention will at once suggest themselves to those skilled in the art to which the invention relates by a reading of the following specification in connection with the accompanying diagrams, wherein:

Fig. 1 shows an arrangement by which it is possible to bring the television, the speech

and the synchronizing signals all within a 100 kilocycle band;

Fig. 2 conventionally illustrates one form of transmitting apparatus for accomplishing the results illustrated by Fig. 1; and,

Fig. 3 conventionally illustrates a receiving system which may be used in cooperation with the transmitter shown by Fig. 2.

Now making reference to the accompanying drawings, it will be noted from Fig. 1 that the television signal is 43 kilocycles wide and that when using both side bands thereof the space occupied for the television signal is, in all, 86 kilocycles. The voice and synchronizing frequencies are, according to the present invention, distributed about a carrier frequency located at 50 kilocycles, for example, from the television carrier frequency.

It has been found in commercial practice that by providing for speech varying from 0 to 5 kilocycles most satisfactory results are obtainable. These speech frequencies up to 5 kilocycles may then be used to modulate the speech carrier located at approximately 50 kilocycles from the television carrier frequency. Upon this secondary carrier frequency a single 6 kilocycle tone may be impressed for the purpose of obtaining proper synchronization between the transmitter and receiver.

While, for the purpose of giving concrete illustrations of one form of our invention, we have illustrated and assigned definite values to the various carrier frequencies and wave bands, it is, of course, to be recognized that these values may be varied within wide limitations without departing from the spirit and scope of the invention, and that all values of frequencies illustrated and described are to be regarded as merely illustrative and not limiting.

Now referring to Fig. 2, showing a form of the transmitter apparatus, 1 designates an arrangement, such as appropriately connected photoelectric elements for picking up the television signal. This television signal is then preferably used to modulate, by means of modulator 3, a carrier frequency of 2043 kilocycles generated by a generator 5 of any desired and suitable character. It will be

noted that the generator frequency has been chosen as 2043 in a purely arbitrary manner, being equal to 2000 kilocycles plus the 43 kilocycle modulation so as to bring the lower limit of the modulated carried frequency as 2000 kilocycles and the upper limit thereof to 2086 kilocycles, for the purpose of bringing the illustrated television signal wave band within the limit, for example, of between 2000 and 2100 kilocycles, when all signals, such as television, speech and synchronizing, are utilized.

Similarly, voice modulation is applied or impressed upon a microphone and amplifier or any other suitable arrangement 7 and passed therefrom through a filtering apparatus 9 which passes frequencies varying between zero and 5 kilocycles chosen for the speech channel. Similarly, a 6 kilocycle synchronizing tone is produced by any convenient form of arrangement, diagrammatically shown as 11, and both the speech or voice and the synchronizing tones are then applied and used to modulate through modulator 12 a second carrier frequency which may be, for example, 50 kilocycles produced by a generator 13 of any suitable and desired character.

The 50 kilocycle carrier, when modulated by both the voice and the synchronizing tone, is then, in turn, applied through filter 14 passing from 44 to 56 kilocycles by means of the modulator arrangement 3 so as to modulate the previously described 2043 kilocycle carrier frequency. This modulation will then produce the voice and synchronizing side bands existing about a second carrier frequency of a value of 2093 kilocycles, and also produce the same effect about a carrier located at 1993 kilocycles but, as shown conventionally by the diagrammatic illustration at 15, there is provided an output filter 15 which passes only frequencies varying between 2000 kilocycles and 2100 kilocycles, so that the lower side band of the carrier frequency 2043 modulated by the 50 kilocycle generator, which is in turn modulated by both voice and the synchronizing tones, is cut off and only one side band existing at 2093 kilocycles is transmitted.

Modulators 3 and 12 are of a type which will prevent the side band frequencies from beating together. For example in the case of modulator 12 the input frequencies are 0-5 kilocycles, 6 kilocycles, and 50 kilocycles. The output frequencies to the filter 14 are 44 kilocycles, 45-50 kilocycles, 50-55 kilocycles, and 56 kilocycles. The frequencies which would be obtained if 0-5 kilocycles beat with the 6 kilocycles, do not exist.

It will thus be seen that, from the antenna system 17, signals varying between 2000 and 2100 kilocycles are transmitted. These signals may be received in any appropriate manner by a receiving system, for example, of

the type conventionally illustrated by Fig. 3 of the accompanying drawings.

Signals transmitted from the transmitter of Fig. 2 may be received by means of a receiving antenna system 19 and directed therefrom through a filtering and amplifying apparatus 21. The filter 21 is preferably so adjusted that it passes frequencies varying only between 2000 kilocycles and 2100 kilocycles. Connected with the output of the filter and amplifying apparatus 21 is a detector 23 to which a frequency corresponding to the carrier frequency for the television signal, namely, 2043 kilocycles is applied by means of generator 25.

The output from the detector 23 is then passed through two separate filtering systems, one, "A", being for the television signal channel and the other, "B", being for the voice and synchronizing signal channel.

In channel "A", for the television signal, we have provided a filter system 27 so arranged as to pass frequencies varying between zero and 43 kilocycles and the output of this filter is then passed through in appropriate form of amplifying arrangement 29 for the purpose of amplifying the television signals, and the amplified signals are then impressed upon a television indicator 31, which may be, for example, a neon glow lamp (not specifically shown), arranged to produce a glow behind the usual type of Nipkow disk, for example.

In the channel "B" we have provided a filtering system 33 arranged to pass frequencies varying, for example, between 43 and 57 kilocycles which will cover the band required for the modulation produced by both the speech or voice frequency and the synchronizing frequency. From the output of this filter 33 the speech and synchronizing energy is passed to a detector 35 upon which is impressed the frequency of a local oscillator at 50 kilocycles, so as to beat with the impressed frequencies of 43-57 kilocycles. Any appropriate form of generator 37 may be provided for generating the 50 kilocycle tone.

The beat frequency output from the detector 35 is then directed to an amplifying system 39 from which it is applied to a pair of parallelly connected filters 41 and 43. The filter 41 is preferably a low pass filter arranged to pass between zero and 5 kilocycles and then direct its output to any appropriate form of speech indicating apparatus 45, for example, a loud speaker, and the output of the 6 kilocycle band pass filter 43 may be applied and directed to any appropriate form of synchronizing arrangement, for example, an arrangement of the type claimed and described by copending application of T. A. Smith, Serial No. 322,704, filed November 30th, 1928 (Dkt. No. 3107) for the purpose of synchronizing the receiving arrangement with that of the transmitter.

It will, of course, be recognized that the local oscillator 37 generating 50 kilocycles is not absolutely necessary at the receiver when the 2093 kilocycle carrier is transmitted, but if the 2093 carrier frequency above described is not transmitted as, for example, in a balanced amplifier or suppressed carrier frequency system, then, of course, it will be recognized that the local oscillator 37 is essential to the system.

10 In addition, it will be recognized that various modifications of the scheme herein disclosed may be provided and these, for example, may consist in connecting a circuit broadly tuned to frequencies varying between 2000 kilocycles and 2100 kilocycles to the receiving antenna system 19, and then detecting these signals and to the output of the detecting system connecting a filtering system passing a maximum of 43 kilocycles. By means 20 of appropriate amplifiers these frequencies may be used to produce the television image at the receiver.

Also, connected to the output of the detector, last described, we may provide, if desired, a second circuit tuned to frequencies varying by 6 or 7 kilocycles in either direction from the 50 kilocycle frequency produced at the receiver. These signals are then detected in the usual manner and the output from this second detector may then be connected with a band pass filter passing from zero to 5 kilocycles for the speech frequency and also connected with a sharply tuned circuit tuned to the 6 kilocycle synchronizing signal. It will, of course, be recognized that certain disadvantages are inherent in a system of the last named type since the energy of the voice and synchronizing signals is substantially decreased and in the event of bad fading conditions, these signals might be totally obliterated.

Also, as a further modification, it would be possible to couple with the receiving antenna 19 a filter system passing between 2000 kilocycles and 2086 kilocycles for the purpose of obtaining a television signal and also parallelly connecting a second filtering and amplifying system in which the filter was tuned 50 2093 kilocycles plus or minus the 6 kilocycle modulation impressed thereon for obtaining the voice and synchronizing signals in a manner similar to that last described.

It is also conceivable that we may provide, 55 if desired, at the transmitter a filtering system arranged to cut off at 2043 kilocycles, for example, should this be desirable, and thus only transmit a single side band of the television signal although with filtering systems 60 arranged to give a sharp cutting off at the lower and upper limits this is not essential since the modulation about 1993 kilocycles signal in nowise effects the television signals, since the voice and synchronizing signals 65 are not capable of modulating each other

by cross modulation effects to any appreciable extent.

While we have used the terms speech, voice, and music as forming the sounds accompanying the television signals and related thereto it should be understood that these terms are intended to include sound of every type and description, whether produced naturally or artificially.

However, arrangements falling within the scope of the present disclosure will at once suggest themselves to those skilled in the art and we, therefore, desire to be limited in the arrangements which we may use only in so far as the scope of the hereinafter appended claims necessitates and we may feel free to make any and all modifications of the invention falling fairly within the spirit and scope of the hereinafter appended claims.

Having now described our invention what we claim and desire to secure by Letters Patent is the following:

1. In a television system, means for producing and transmitting television signals lying within a relatively large proportion of a predetermined and chosen wave band, means for simultaneously producing and transmitting speech signals lying within a relatively small portion of the said predetermined chosen wave band, and means for simultaneously producing and transmitting synchronizing signals occupying a minute portion of said predetermined chosen wave band.

2. In a television system, means for producing television signals falling within predetermined frequency range, means for simultaneously producing speech signals to accompany the television signals, and means for also simultaneously producing a synchronizing frequency accompanying both said television signal frequency and said speech signal frequency, means for simultaneously transmitting all of said television, speech and synchronizing signal frequencies, and means for receiving and distinguishing between each of said various frequencies, whereby the synchronizing signal frequency controls the synchronization of the television signal at the transmitter and receiver and the speech signals accompany the television signal as the same is received.

3. A system for simultaneously receiving speech, television and synchronizing signals all of which are produced and occur within a predetermined chosen frequency band, which includes, means for selecting received signals falling within the said predetermined frequency band, means for determining and selecting the television signal from said frequency band, means for jointly selecting and distinguishing the speech and synchronizing frequency from said predetermined frequency band, and means for filtering and distinguishing between the said speech and synchronizing frequencies, whereby the synchro-

- nizing frequencies control the synchronization of the television signals and the speech signals accompany the television image as reproduced in proper time relationship.
5. In a television system, means for producing television signals varying in frequency over a predetermined frequency band, means for producing a carrier frequency, means for modulating said carrier frequency by said television signals, means for producing speech signals simultaneously with the production of said television signals, means for producing a synchronizing signal frequency for maintaining synchronism in 10 said television system, means for producing a second carrier frequency, means for modulating said second carrier frequency by said speech and voice frequency, and means for modulating in turn said first named carrier 15 frequency by said last named modulated second carrier frequency, and filtering means for eliminating one side band produced by said first named frequency modulated by said secondary modulated carrier frequency, and 20 means for transmitting all of said signals simultaneously within a predetermined frequency band.
5. In a television system, means for producing a carrier frequency, means for producing television signals and modulating said carrier frequency therefrom in a manner such that the modulated carrier covers a relatively large portion of a predetermined frequency band for the television signal, the 30 speech signal accompanying the same and a synchronizing signal frequency for maintaining synchronization in the said television system, means for simultaneously producing speech and synchronizing signals and modulating the said carrier frequency thereby in a manner such that the modulation produced by said speech signals and said synchronizing signals lies external to the frequency band covered by said television signals, and 40 means for transmitting the said signals.
6. The method of simultaneously transmitting television, speech and synchronizing signals all lying within a predetermined chosen frequency band, which includes, 50 modulating a carrier frequency by television signals varying over a predetermined frequency band, producing a secondary carrier frequency, modulating said secondary carrier frequency by a speech frequency varying over a predetermined frequency range and by a synchronizing frequency of constant value, modulating said first named carrier frequency by said speech and synchronizing signal modulated secondary carrier frequency, limiting the frequency band covered by said doubly modulated carrier frequency, and transmitting the said television, speech and synchronizing frequencies all within a predetermined chosen frequency band.
- 65 7. In a television system, a combination of a transmitter and a receiver, and means for simultaneously transmitting from said transmitter television, speech and synchronizing signals all lying within a predetermined chosen frequency band, and means for receiving and distinguishing between all of said television, speech and synchronizing signals at the receiver, whereby television images are produced at the receiver and synchronized with the movements of the television subject at the transmitter, and the speech record is simultaneously transmitted and received so as to bring the speech record in proper phase relationship with the movements of the television subject.
8. In a television receiving system for receiving combined television, speech and synchronizing frequencies all lying within a predetermined wave band, means for receiving signals and limiting the reception thereof to the predetermined chosen frequency band, means for detecting all of said signals and filtering the same to separate television signals from the speech and synchronizing signals, means for detecting the speech of synchronizing signals, and means for filtering the rectified output of said last named detector and a distinguishing between the speech and synchronizing signals, whereby synchronization of the television signal is obtained from the synchronizing signal and a sound record occurring simultaneously with the television signal is produced by the speech frequency.
9. In a television system, means for simultaneously receiving combined television, synchronizing and speech signal, means for detecting each of the received signals, filter means for separating each of said signals one from the other, and means for amplifying each of said signals and producing from the same a television image, synchronized movements of the television image, and an accompanying speech record.
10. In a television and sound transmission system having the signals confined within a continuous frequency band, means for producing and transmitting television signals grouped about a predetermined carrier frequency and occupying a relatively large portion of the frequency band, and means for simultaneously producing and transmitting related sound signals grouped about a second predetermined sound carrier frequency separated from the television carrier and adjacent thereto and arranged to occupy a relatively small portion of the said frequency band.
11. The combination claimed in claim 10 including, in addition, means for producing and transmitting synchronizing signals grouped about said sound carrier so as to occupy the upper and lower limits of the frequency band selected therefor.
12. In a television system, means for simul-
